(57) **CLAIM**

The ornamental design for a pet chew toy brush, as shown and described.

DESCRIPTION

FIG. 1 is a perspective view showing our new design;

FIG. 2 is a front elevational view;

FIG. 3 is a rear elevational view;

FIG. 4 is a first side elevational view;

FIG. 5 is a second side elevational view;

FIG. 6 is a top plan view; and,

FIG. 7 is a bottom plan view.

Any broken lines denote probable environmental structure and are not part of the claimed design.

The broken line structure beginning at the base of the bristles and showing an elongated handle is included for the purpose of illustrating a portion of the article that forms no part of the claimed design.

1 Claim, 6 Drawing Sheets
